CHECK FOR PICKER STICKS

John W. Jones, Greenville, S. C., assignor to
Harriett K. Bellwood, Greenville, S. C.

Application September 24, 1942, Serial No. 459,549

7 Claims. (Cl. 139—150)

My invention relates to looms and has particular reference to checks for picker sticks.

An important object of the invention is to provide a device of the above mentioned character which is arranged adjacent to the oscillating stand, and which will check the movement of the picker stick in opposite directions.

A further object of the invention is to provide a checking device of the above mentioned character having parts which are mounted upon the shoe and oscillating stand of the conventional loom without altering the construction of the same.

A further object of the invention is to provide a device of the above mentioned character which will dispense with the use of the ordinary spring actuated drum to return the picker stick to the outer position.

A further object of the invention is to provide a checking device for the picker stick which is simple in construction and durable and dispenses with the use of the conventional picker stick check strap.

A further object of the invention is to provide a device of the above mentioned character, which is adjustable to regulate the checking action upon the picker stick and the yielding action which returns the picker stick to the outer position.

Other objects and advantages of the invention will be apparent during the course of the following description.

In the accompanying drawing forming a part of this application and in which like numerals are employed to designate like parts throughout the same,

Figure 1 is a side elevation of a picker stick check embodying my invention, showing the same in use, and the picker stick in the intermediate or vertical position.

Figure 2 is a similar view, parts broken away, showing the picker stick in the outer inclined position.

Figure 3 is an exploded perspective view of the unit which is mounted upon the oscillating stand.

Figure 4 is a transverse section taken on line 4—4 of Figure 2.

Figure 5 is a perspective view of the upper unit which is mounted upon the shoe.

Figure 6 is a side elevation of the upper unit showing the relative position between the same and the bumpers when the picker stick is in the outer inclined position.

Figure 7 is a similar view showing such rela-

tive position when the picker stick is in the intermediate or vertical position, and,

Figure 8 is a similar view showing the relative position when the picker stick is in the inner inclined position.

In the drawing, wherein for the purpose of illustration is shown a preferred embodiment of my invention, the numeral 10 designates a loom frame, carrying the lay rock shaft 11. Rigidly mounted upon the rock shaft 11 is an oscillating stand 12, having a shoe 13 mounted thereon in the usual manner. The shoe 13 oscillates with the stand 12 and also rocks longitudinally of the stand as is customary. As more clearly shown in Figure 4, the stand 12 has a depending arm or bracket 14, formed integral therewith and positioned at one longitudinal edge of the stand. The shoe 13 is provided with the usual opening for receiving the lower end 15 of a picker stick, secured to the shoe by a heel bolt 16, passing through a cap 17 and the shank 18 of the shoe. The shank 18 also has screw-threaded engagement with an adjusting screw 19, engaging a parallel-tongue 20. The set-screw 19 has a lock-knot 21. By manipulating the bolt 16 and set screw 19 the picker stick 15 may be angularly adjusted with relation to the shoe 13. The picker stick 15 is thrown inwardly by suitable means shown at 22'. The construction thus shown and described is that of the conventional loom.

My improved picker stick check includes a lower unit comprising substantially horizontal preferably rigid straps 22 and 23, arranged beneath the oscillating stand 12 and extending substantially parallel therewith. These straps are preferably formed of metal and their inner ends overlap and are provided with longitudinal slots 24. At their outer ends the straps 22 and 23 carry upstanding ears or extensions 25, in turn carrying bolts 26. These bolts pass through openings formed in bumpers 27, which are preferably cylindrical. The bumpers 27 are preferably formed of leather or other fibrous material and the bolts 26 have screw threaded ends to engage within screw threaded openings 28 formed in ears 25. By adjusting the bolts 26 the bumpers may be turned upon the bolts to compensate the wear and subsequently again clamped to the ears. The numeral 27' designates a substantially horizontal support plate arranged beneath the oscillating stand and above the straps 22 and 23. This plate is preferably formed of metal and is preferably rigid. The plate 27 has a lateral extension 28' carrying

a depending arm 29, provided with an opening 30 near its lower end. The plate 27' has an opening 31, to receive a bolt 32, passing through the slots 24, and carrying a nut 33. By adjusting the bolt 32 the straps 22 and 23 may be adjusted longitudinally of the plate 27' and clamped thereto in the selected adjusted position. In this manner the distance between the bumpers 27 may be varied. The plate 27' is also provided with a longitudinal slot 34.

The lower unit is rigidly attached to the oscillating stand 12, and to effect this attachment the depending arm 29 is placed upon the inner face of the depending arm 14, and these parts are clamped together by a bolt 35, passing through the opening 30 and an opening 36 in the arm 14. The usual spring operated drum which returns the picker stick to the outer position is omitted with its bolt or attaching means which entered the opening 36.

The numeral 37 designates a hook, the upper end of which is screw threaded and passes through the longitudinal slot 34 and carries nuts 38, above and below the plate 27'. A heel-strap 39 is secured to the lower end of the picker stick and is connected with a pull-spring 40, the opposite end of which is connected with the hook 37. The spring 40 and heel-strap 39 swing the picker stick to the outer inclined position. The tension of the pull-spring 40 may be regulated by adjusting the hook 37 longitudinally of the plate 27'.

It is thus apparent that the lower unit is mounted upon the oscillating stand without in any way altering the construction of the stand.

The upper unit of the device comprises an inverted V-shaped holder or head 41, which is preferably rigid and preferably formed of metal. This holder has an attaching plate 42 rigidly secured thereto at its apex. The plate 42 has upper and lower openings 43 and 44. The upper opening 43 receives the set-screw 19 while the lower opening 44 receives the bolt 16. The holder 41 is provided near its lower ends with inwardly facing bolts 45, rigidly secured thereto by any suitable means. These bolts 45 pass through longitudinal slots 46 formed in preferably rigid arms 47. These arms are disposed inwardly of the holder 41 and diverge downwardly and their upper ends are slightly bent laterally, as shown at 47', to permit of a proper swinging action of the arms 47 upon the bolts 45. The inner or upper ends of the arms 47 contact with a wall 48 included in the head or holder 41 to prevent displacement of the arms 47. The inner ends of the bolts 45 are screw-threaded for receiving nuts 49, engaging springs 50 carried by the bolts 45. It is thus apparent that the arms 47 will swing upon the bolts 45 in the plane of the holder 41, but not at a right angle to this plane. The tension of the springs 50 may be regulated by adjusting the nuts 49.

It is thus apparent that the upper unit is mounted upon the shoe 13 without altering the construction of the shoe.

When the lower unit is assembled upon the oscillating stand and the upper unit mounted upon the shoe, the downwardly diverging arms 47 are arranged between and contact with the bumpers 27. When the picker stick is swung to the outer inclined position the arm 47 to the right, Figures 2 and 6, compresses its engaging spring 50, thus checking the outward movement of the picker stick. When the picker stick is in the intermediate or vertical position, Figures 1 and 4,

the arms 41 engage the bumpers but do not compress the springs and hence there is little, if any, stopping or checking action exerted upon the picker stick. When the picker stick is swung to the inner inclined position, the arm 47 to the left, Figure 8, compresses its engaging spring and a checking action is exerted upon the picker stick. Ordinarily the device will exert a greater checking action upon the picker stick upon the inward swinging movement of the picker stick than upon its outward swinging movement. It exerts a checking action upon the picker stick when swinging in both directions. By adjusting the nuts 49 the degree of checking action in either or both directions of the movement of the picker stick may be regulated or varied, as desired.

The bumpers 27 are adjustable to vary the distance between them and this adjustment may be employed to compensate for the wear upon the bumpers or may also be employed to regulate the extent of checking action that the arms 47 exert upon the picker stick.

It is to be understood that the form of my invention herewith shown and described is to be taken as a preferred example of the same, and that various changes in the shape, size, and arrangement of parts may be resorted to, without departing from the spirit of my invention or the scope of the subjoined claims.

Having thus described my invention, what I claim is:

1. A picker stick check for a loom having a picker stick, a shoe secured to the picker stick and an oscillating stand, said check including a lower unit mounted upon the oscillating stand and including spaced bumpers, an upper unit mounted upon the shoe and including resilient devices engaging the bumpers.

2. A picker stick check for a loom having a picker stick, a shoe secured to the picker stick and an oscillating stand, said check including a lower unit mounted upon the oscillating stand and spaced bumpers mounted upon the lower unit, an upper unit mounted upon the shoe and including a holder, arms carried by the holder and arranged to engage the bumpers, and resilient means acting upon the arms to oppose their relative movement with respect to the holder.

3. A picker stick check for a loom having a picker stick, a shoe secured to the picker stick and an oscillating stand, said check including a lower unit mounted upon the stand, spaced bumpers carried by the lower unit, an upper unit mounted upon the shoe, arms arranged to engage the inner sides of the bumpers, means to connect the arms with the holder so that the arms may swing with relation to the holder, and resilient means to oppose the swinging movement of the arms.

4. A picker stick check for a loom having a picker stick, a shoe secured to the picker stick and an oscillating stand, said check including a lower unit mounted upon the stand, spaced bumpers carried by the lower unit, an upper-unit mounted upon the shoe, arms arranged to engage the bumpers and having openings formed therein, bolts connected with the holder and passing through the openings in the arms, springs carried by the bolts and engaging the arms, and nuts carried by the bolts to engage the springs and regulate their tension.

5. A picker stick check for a loom having a picker stick, a shoe secured to the picker stick and an oscillating stand, said check including a

lower unit mounted upon the stand, spaced bumpers carried by the lower unit, an upper unit mounted upon the shoe and including a holder having downwardly diverging sides, downwardly diverging arms arranged within the holder and engaging the inner sides of the bumpers, elements pivotally connecting the arms with the sides, resilient elements carried by the first named elements and engaging the arms, and adjustable means to regulate the tension of the 10 resilient elements.

6. A picker stick check for a loom having a picker stick, a shoe secured to the picker stick and an oscillating stand having an arm provided with an opening, a plate arranged beneath the oscillating stand and having an arm provided with an opening, an element passing through the 15 openings in the arms to secure them together, straps longitudinally adjustably mounted upon

the plate, bumpers mounted upon the straps, a holder mounted upon the shoe, and resilient devices carried by the holder and arranged to engage the bumpers.

5 7. A picker stick check for a loom having a picker stick, a shoe secured to the picker stick and an oscillating stand having an arm, a plate arranged beneath the oscillating stand, means to secure the plate to the arm, straps longitudinally adjustably mounted upon the plate, bumpers mounted upon the straps, a holder mounted upon the shoe, resilient devices carried by the holder and arranged to engage the bumpers, and elements secured to the plate, and resilient means connected with the picker stick to swing the same outwardly and connected with said element.

JOHN W. JONES.
